(57) CLAIM

The ornamental design for letter shaped liquor bottle, as shown and described.

DESCRIPTION

FIG. 1 is a perspective view of an alternate embodiment of the letter shaped liquor bottle, or portion thereof, showing my new design;

FIG. 2 is a front view thereof;

FIG. 3 is a right view thereof;

FIG. 4 is a left view thereof;

FIG. 5 is a top view thereof; and,

FIG. 6 is a bottom view thereof.

Any broken lines in the figures are shown for illustrative purposes only and form no part of the claimed design.
